(57) **CLAIM**

The ornamental design for a dock with an integral dispenser, as shown and described.

DESCRIPTION

FIG. 1 is a perspective view of a dock of the present design, the dock comprising an integral dispenser and an opening.

FIG. 2 is a left side view of the dock of FIG. 1, the right side view being a mirror image thereof.

FIG. 3 is a rear view of the dock of FIG. 1.

FIG. 4 is a front view of the dock of FIG. 1.

FIG. 5 is a top view of the dock of FIG. 1.

FIG. 6 is a perspective view of the dock of FIG. 1 showing a scrubber disposed within the opening of the dock, the scrubber shown in dashed lines.

FIG. 7 is a left side view of the dock of FIG. 1 showing a scrubber disposed within the opening of the dock, the scrubber shown in dashed lines, the right side view being a mirror image thereof.

FIG. 8 is a rear view of the dock of FIG. 1 showing a scrubber disposed within the opening of the dock, the scrubber shown in dashed lines.

FIG. 9 is a front view of the dock of FIG. 1 showing a scrubber disposed within the opening of the dock, the scrubber shown in dashed lines; and,

FIG. 10 is a top view of the dock of FIG. 1 showing a scrubber disposed within the opening of the dock, the scrubber shown in dashed lines.

The dashed lines shown in the figures are for illustration only and do not form part of the claimed design.
